[57] CLAIM

The ornamental design for an organ, substantially as shown and described.

DESCRIPTION

FIG. 1 is a front, top and left side perspective view of the organ showing my new design;

FIG. 2 is a right side elevational view; and

FIG. 3 is a front elevational view.

The back of the organ is conventional. The upstanding portion of the music desk is transparent. The fabric covering the lower front board and portions of the organ sides is continuous throughout the boundaries thereof. The left side of the organ, is a mirror image of the right side as shown.

The structure not shown on the upper and lower control panels directly above the keyboards is conventional.
